Patent No. D. 237,597

Patented November 11, 1975

Richard Allen Clarke, William James Chvala and Raymond Edward De Witte

Application having been made by Richard Allen Clarke, William James Chvala and Raymond Edward De Witte, the inventors named in the patent above identified, and PepsiCo, Inc., Purchase, New York, a corporation of Delaware, the assignee, for the issuance of a certificate under the provisions of Title 35, Section 256, of the United States Code, deleting the name of Raymond Edward De Witte as a joint inventor, and a showing and proof of facts satisfying the requirements of the said section having been submitted, it is this 8th day of August 1978, certified that the name of the said Raymond Edward De Witte is hereby deleted from the said patent as a joint inventor with the said Richard Allen Clarke and William James Chvala.

FRED W. SHERLING,
Associate Solicitor.
